UNITED STATES PATENT OFFICE.

CHARLES E. SCRIBNER, OF CHICAGO, ILLINOIS, ASSIGNOR TO THE WESTERN ELECTRIC MANUFACTURING COMPANY, OF SAME PLACE.

BATTERY TELEPHONE-TRANSMITTER.

SPECIFICATION forming part of Letters Patent No. 251,800, dated January 3, 1882.

Application filed May 14, 1881. (No model.)

To all whom it may concern:

Be it known that I, CHARLES E. SCRIBNER, of Chicago, Illinois, have invented a certain new and useful Improvement in Battery Telephone-Transmitters, of which the following is the specification.

My invention relates to battery telephone-transmitters in which the electrodes consist of disks of carbon or attenuated points which are so connected with the diaphragm that its vibrations cause a variation in the resistance of the contact of the electrodes which are placed in a local circuit passing through the primary of an induction-coil. The varying current of the local circuit induces a current with like variations in the main line which passes through the secondary of the induction-coil.

The object of my invention is to increase the volume and distinctness of the transmitted speech, and this I have accomplished by the use of two battery transmitters, placing them in close proximity to each other, so that their diaphragms can be acted upon simultaneously by the same sounds, and combining with them induction-coils, so that the secondaries are in line in the main circuit, while the primaries are independent of each other.

In the drawing, *a* and *b* represent Edison telephone-transmitters, placed near each other, so that the same sounds will act upon both of their diaphragms.

a' and *b'* are induction-coils. The telephone-line passes through the secondaries of both induction-coils, and the currents of the two local batteries *a''* and *b''*, when varied by the synchronous vibrations of the diaphragms of the two transmitters, act together and induce a current with like variations in the telephone-line. Thus the efficient strength of the induced current may be increased about fifty per cent. I have used a greater number of transmitters with their local circuits and induction-coils combined with a single telephone or main circuit passing through the secondaries of all their induction-coils; but the efficient strength of the induced current does not increase as rapidly after the second transmitter is added.

I claim—

The combination of two or more battery-transmitters so placed as to be acted upon simultaneously by the same sounds, and each being in an independent local circuit, a part of which forms the primary of an induction-coil, while the several secondaries are in line in the main line.

CHARLES E. SCRIBNER.
